(57) **CLAIM**

The ornamental design for a door threshold corner seal, as shown and described.

DESCRIPTION

FIG. 1 is a perspective view of the door threshold corner seal;

FIG. 2 is a bottom view of the door threshold corner seal of FIG. 1;

FIG. 3 is a top view of the door threshold corner seal of FIG. 1;

FIG. 4 is a left side view of the door threshold corner seal of FIG. 1;

FIG. 5 is a front view of the door threshold corner seal of FIG. 1;

FIG. 6 is a rear view of the door threshold corner seal of FIG. 1; and,

FIG. 7 is a right side view of the door threshold corner seal of FIG. 1.

The broken lines illustrate portions of the door threshold corner seal that form no part of the claimed design.

1 Claim, 5 Drawing Sheets
